UNITED STATES PATENT OFFICE.

CHARLES A. MUDDIMAN, OF WASHINGTON, DISTRICT OF COLUMBIA.

HOT-WATER BOILER OR TANK.

1,355,413.

Specification of Letters Patent. Patented Oct. 12, 1920.

Application filed May 22, 1920. Serial No. 383,584.

To all whom it may concern:

Be it known that I, CHARLES A. MUDDIMAN, a citizen of the United States, and resident of Washington, District of Columbia, have invented certain new and useful Improvements in Hot-Water Boiler or Tanks, of which the following is a specification.

My invention relates to hot water boilers or tanks, and more particularly to boilers or tanks having a heat insulating jacket thereon, and has for one of its principal objects the provision of such an insulating jacket having a higher efficiency than any heretofore known.

Another object is to provide an insulating jacket that may be put on the boilers at the factory and shipped without being damaged.

Another and very important object is to provide an insulating jacket having a plurality of comparatively small air cells, thereby preventing the circulation of any great amount of air when heated.

Still a further object is the provision of an insulating jacket that will combine cheapness, lightness, and durability, in a structure having a high efficiency.

Heretofore it has been the practice to insulate boilers "on the job," that is, after they were installed, and this practice has led to poor insulations due to the fact that the workmen were careless or inexperienced, and also caused much inconvenience to the occupants of the premises where the boiler was installed, by the use of the insulating mixtures. However, the practice of insulating the boilers on the premises was a necessary evil, since no insulation was known that was not too fragile to stand shipping. It has also been the practice to apply the insulation directly to or against the boiler, and while this was much better than no insulation at all, it was not a perfect insulation, and had a tendency to become loosened due to the expansion and contraction of the boiler and the sweating thereof, and also due to the fact that it could not properly adhere to the smooth boiler surface.

All of the above disadvantages and evils have been overcome by my invention. The insulating casing may be applied at the factory and shipped without danger of breaking, the construction as shown provides a plurality of dead air chambers between the casing and the boiler wall, thereby creating a perfect insulation, and the casing is spaced

away from the boiler wall and provided with a mesh base, thereby forming an ideal lock for the fibrous insulating material.

The above and other objects and advantages will be more fully described in the following specification, and illustrated in the accompanying drawings, in which—

Fig. 1 is a side elevation showing my improved insulating casing applied to a boiler.

Fig. 2 is a side elevation with the several parts of the casing broken away to show the structure thereof.

Fig. 3 is a top plan view of a boiler constructed in accordance with my invention, with the insulating casing removed to show the strips that support it.

Fig. 4 is a bottom plan view of a boiler having a portion of the insulating casing broken away.

Referring particularly to the drawings, the numeral 2 designates the boiler which may be of any desired and well-known construction.

A plurality of vertical strips or ribs 3 and horizontal strips or ribs 4 of non-heat absorbing, and non-combustible material such as asbestos board, are secured to and spaced around the periphery of the boiler in such a manner as to form a checkerwork 85 of cells or spaces 5. Other strips or ribs 6 are secured to and spaced in spoke-like formation on the top and bottom faces of the boiler forming other cells or spaces 7.

A mesh base 8 which may be expanded metal, wire mesh, or the like, is mounted over the strips 3, 4, and 6, forming a surrounding perforated wall around the tank or boiler 2.

A non-heat absorbing and non-combustible plaster, such as asbestos plaster, is applied over the base 8, care being taken to force it through the mesh, thus keying or locking it in place, and a sufficient amount is applied to form a casing 9 about one-inch in thickness.

After the casing 9 has been applied and while it is still in a plastic state, a canvas or other textile covering 10 is applied over and forced into the casing so that it becomes impregnated therewith and adheres thereto.

After the casing 9 has hardened, the whole structure will be an integral and solid mass, having the dead air spaces or cells 5 110

between the inner wall of the casing 9 and the outer periphery of the boiler, and will be of sufficient strength to withstand the shocks received in shipping or transporting the boilers from place to place.

Any expansion and contraction of the metal boiler 2 or sweating of its walls will in nowise affect the casing, due to the air cells 5.

10 While I have shown and described but one embodiment of my invention in combination with a hot water boiler or tank, it will be understood that I do not wish to be limited to such a combination, since various 15 uses may be found for my improved casing, such as applying it to furnaces or other heat supplying means.

Various minor changes and modifications in structure and combination of parts will 20 readily suggest themselves to those skilled in the art, and, therefore, I wish it expressly understood that such minor changes and modifications may be made without departing from the spirit of my invention as 25 described in the appended claims.

What I claim is—

1. In combination with a receptacle, an insulating casing, comprising a plurality of rib members spaced apart on the outer 30 surface of said receptacle forming a plurality of cell like depressions, a perforated base mounted over said ribs so as to inclose said receptacle, and a plastic, non-heat absorbing material mounted over said perforated base and secured thereto.

2. In combination with a receptacle, an insulating casing, comprising a plurality of rib members spaced apart on the outer sur-

face of said receptacle forming a plurality of cell like depressions, a perforated base 40 mounted over said ribs so as to inclose said receptacle, a plastic non-heat absorbing and non-combustible material mounted over said perforated base, and a textile binder mounted over and forced into said plastic composition.

3. The combination with a hot water boiler having a cylindrical outline, of an insulating casing, comprising a plurality of vertical and horizontal non-heat absorbing 50 rib members spaced around its side walls forming a plurality of cell like depressions, other ribs spaced in spoke-like formation on the ends of said boiler, and a non-heat absorbing and non-combustible covering 55 mounted over said ribs and inclosing said receptacle.

4. The combination with a hot water boiler having a cylindrical outline, of an insulating casing, comprising a plurality of vertical and horizontal non-heat absorbing rib members spaced around its side walls forming a plurality of cell like depressions, other ribs spaced in spoke-like formation on the ends of said boiler, a perforated base 60 member over all of said ribs so as to entirely inclose said receptacle, a layer of plastic non-heat absorbing and non-combustible material mounted over said perforated base and secured thereto, and a textile binder 70 mounted over, secured to, and inclosing said layer of plastic material.

In testimony whereof I have hereunto set my hand.

CHARLES A. MUDDIMAN.
